FLUSH BOLT.

1,116,617.

Specification of Letters Patent. Patented Nov. 10, 1914.

Application filed November 16, 1912. Serial No. 731,812.

To all whom it may concern:

Be it known that I, ALBERT A. PAGE, a citizen of the United States, residing in East Haven, county of New Haven, and 5 State of Connecticut, have invented certain new and useful Improvements in Flush Bolts, of which the following is a full, clear, and exact description.

This invention relates to flush bolts, and 10 the primary objects of the invention are to provide a construction in which the operating lever or finger piece is so connected with the bolt proper as to exert a powerful leverage thereon; to provide an improved 15 arrangement of the spring or springs which hold the bolt in its protracted and retracted positions respectively; to furnish means for effectively housing and protecting certain operative parts and for insuring the mortising of the door or other part to an extent 20 sufficient to prevent binding; and to increase the simplicity, strength and durability of devices of this general class.

To these and other ends the invention 25 consists in the novel features and combinations of parts to be hereinafter described and claimed.

In the accompanying drawing, illustrating a preferred embodiment of the invention, Figure 1 is a side elevation of the flush bolt showing the bolt proper in its retracted position, Fig. 2 is a similar view showing the bolt protracted, Fig. 3 is a front face view of the device, Fig. 4 is a rear face 35 view, Fig. 5 is a section on line 5—5 of Fig. 1, Fig. 6 is a section on line 6—6 of Fig. 2, and Fig. 7 is a fragmentary detail section on line 7—7 of Fig. 4.

Referring to the drawing, 10 indicates 40 the usual face plate or supporting plate having the customary longitudinal recess or cutaway portion 11 in which the actuating lever or finger piece 12 is housed. The customary bolt 13 is slidably mounted on the 45 rear face of the plate 10 in perforated lugs or guides 14, 15. The device illustrated is what is termed an extension flush bolt, the bolt 13 being provided with an extension rod or bolt 16, (only partially shown) but 50 this feature of the construction is not material to the present invention.

In carrying out my invention, I provide 55 the face plate 10 with integral rearwardly extending cheeks or side plates 17 located alongside the recess 11, and the lever 12 is

pivoted or fulcrumed between these cheeks or side plates by means of a pivot pin 18 extending across the space between the cheeks and secured to the latter at its respective ends. The pivot 18 is located intermediate the manipulating end 12^a of the lever 12 and the opposite end 12^b of said lever, which latter end is connected with the bolt 13 by means of a link 19. Hence it will be understood that the lever 12 is a lever of the first order, and as a result a very powerful leverage may be exerted on the link 19 and bolt 13 when the fulcrum is located nearer to the end 12^b of the lever than to the end 12^a, as shown. 70

The working end 12^b of the lever 12 is preferably bifurcated or forked and pivotal connection with the link 19 is effected by setting the adjacent end of the link in the forked portion of the lever and pinning it 75 therein by means of a pivot pin 12^c. The connection between the opposite end of the link and the adjacent end of the bolt is also preferably effected in the same way, the bolt having a forked extremity 13^a in which the 80 adjacent end of the link is pivotally secured by a pin 19^a. The link-connected end of the lever is rounded off or tapered at opposite sides to form a nose, on which a spring or springs 20 act to hold the bolt in the retracted position of Fig. 1 or the protracted position of Fig. 2. I prefer to employ two leaf springs 20 attached to the supporting plate at 21 and having bowed portions 20^a 85 extending parallel to each other and acting on the nose 12^b at opposite sides of the link, as shown in Fig. 4. These springs normally urge the end portion or nose 12^b of the lever toward the face of the supporting plate in order to fully protract or retract the bolt and hold the lever substantially 90 within the lines of the supporting plate, as shown in Fig. 1.

The operation of the device will be obvious for the most part from the foregoing 100 description. Assuming the parts to be in the position shown in Fig. 1, the oscillation of the lever 12 on its pivot 18 will cause the springs 20^b to be forced backward from the face of the plate, thereby putting them under increased tension, and as the manipulating end of the lever passes beyond the center line of the pin 18 (which may be represented by the section line 5—5 of Fig. 1) 105 the springs will force the lever into the po- 110

sition shown in Fig. 2 as soon as the lever is released by the operator. This movement of the lever under the influence of the springs will obviously cause the bolt 13 to be moved quickly from its partly protracted position into its fully protracted position, as is usual in devices of this character. The described operations are reversed when the lever is lifted from the position shown in Fig. 2 for the purpose of retracting the bolt.

The cheeks or side plates 17 not only serve to house and protect the springs but also to guide the link 19, for which purpose said cheeks are provided with lateral extremities 22 confining the link between them, as shown in Fig. 4. Moreover, these cheeks have the even more important function of preventing the parts from binding when the lever is swung out into a position perpendicular to the face of the supporting plate. The width of the cheeks is so chosen that even when the parts are in this position, the cheeks will extend rearwardly beyond the lever, springs and link, and therefore in cutting a mortise sufficiently deep for the cheeks, the carpenter may be sure that when the device is operated none of the parts will bind against the rear or bottom wall of the mortise. In some prior devices considerable trouble in this respect has been encountered as a result of making the mortise too shallow, but this defect is completely remedied by my present construction.

Without limiting myself to the construction shown, I claim:

1. In a flush bolt, the combination with a

supporting plate having separated cheek members projecting laterally therefrom, a sliding bolt carried by the plate and arranged substantially parallel therewith, a pivoted link connected with the bolt, a lever pivotally supported between the cheek plates and having a short arm pivotally connected with the lower end of the link, the width of the lever being substantially equal to the space between the cheek plates, and a plurality of spring parts secured to the supporting plate and engaging the lever on opposite sides of its pivotal connection with the link and lying adjacent the sides of the cheek plate, substantially as described.

2. In a flush bolt, the combination with a supporting plate having laterally extending cheek members spaced apart, each cheek being provided with inturned end portions leaving an intermediate space therebetween, a sliding bolt on the supporting plate, a link pivotally secured to the bolt and projecting between the inturned portions of the cheek plate whereby the link is guided in its movement, a lever pivoted to the plate and having its short arm pivotally connected to the link, and springs engaging the short arm of the lever, substantially as described.

In witness whereof, I have hereunto set my hand on the 15th day of November 1912.

ALBERT A. PAGE.
